THREAD HOLDER FOR MAGAZINES

Herbert A. Whitin, Worcester, Mass., assignor to
 Crompton & Knowles Loom Works, Worcester,
 Mass., a corporation of Massachusetts

Application March 4, 1944, Serial No. 525,069

16 Claims. (Cl. 139—247)

This invention relates to improvements in thread holders for weft replenishing looms and it is the general object of the invention to provide a thread holder capable of handling heavy yarns.

In multi-stack weft replenishing looms the reserve bobbins are arranged in several stacks with their weft ends held above the reciprocating lay by a thread holder which assists in threading a newly replenished shuttle. A form of thread holder which has gone into extensive use employs a pair of geared thread engaging members which are actuated by a motor operating due to loom vibration. When a thread holder of this type is used with bobbins having coarse weft the vibration motor is not always able to turn the gears, especially when the magazine is full of bobbins and the weft ends form a large bundle. It is an important object of my present invention to provide electromagnetic drive means for the gears operating in such manner as to cause turning of the gears even though a large volume of threads is located between them.

Due to loom vibration the bobbins in the several stacks are likely to turn on their axes and slacken their weft ends, and the amount of slackening is more or less proportional to the amount of vibration. It is another object of my present invention to control the circuit of the electromagnetic gear drive by a switch which is closed by a part responding to loom vibration. In this way the electromagnetic drive turns the gears at a rate substantially proportional to loom vibration, and when there is considerable slackening of the weft ends due to vibration there will be a corresponding increase in the operation of the gear driving mechanism.

The thread holder and its gears are mounted on an arm extending outwardly from the magazine and subject to vibration with the loom. I have found that a second member or auxiliary vibrator having a vibration different from that of the holder can be used to close an electric switch. The vibration force will be large enough to close the switch and thus control an electromagnetic device which can exert a larger force sufficient to turn the gears.

With these and other objects in view which will appear as the description proceeds, my invention resides in the combination and arrangement of parts hereinafter described and set forth.

In the accompanying drawing wherein a convenient embodiment of my invention is set forth,

Fig. 1 is a front elevation of a portion of a loom

indicating the location of my improved thread holder,

Fig. 2 is an enlarged plan view of the thread holder looking in the direction of arrow 2, Fig. 1,

Fig. 3 is a side elevation looking in the direction of arrow 3, Fig. 2,

Fig. 4 is a side elevation of the supporting arm, thread holder and auxiliary vibrator looking in the direction of arrow 4, Fig. 1, on an enlarged scale,

Fig. 5 is a view on an enlarged scale of the lower part of Fig. 4 with the cover plate removed and disclosing the operating mechanism within the holder, and

Fig. 6 is a horizontal section on line 6—6, Fig. 5.

Referring particularly to Fig. 1, I have shown a loom frame 10 having picking mechanism 11 for actuating a shuttle S on the lay L. A magazine M preferably of the multi-stack type is secured to the loom frame and has arranged therein bobbins B which are transferred one by one and in well-known manner into the shuttle S. Weft ends, designated generally at W, extend from the bobbins B outwardly from the magazine 10 to a thread holder H. This thread holder is mounted on an arm 12 secured in any approved manner to some part of the magazine, such as the tie rod 13.

The holder H includes in its construction a box-like structure 15 having a vertical side wall 16, a bottom horizontal wall 17 and vertical right and left side walls 18 and 19, respectively, as viewed in Fig. 5. A stationary shaft 20 is rotatably mounted in a bearing 21 fixed with respect to wall 16. This shaft extends into the box 15 and has secured thereto a ratchet wheel 22. The outer end of the shaft extends beyond wall 16 and has secured thereto a gear 23 the teeth 24 of which are smooth for engagement with the weft ends.

A stud 30, see Fig. 5, fixed to the vertical wall 18 has mounted thereon a link 31 in the upper end of which is rotatably mounted a second shaft 32 to which is secured a second thread engaging gear 33 having teeth 34 similar to the teeth 24. The bearing 34 of shaft 32 extends through wall 16 and is capable of lateral movement toward and from bearing 21.

A rod 35 mounted for rotation in the upper end of the box 15 has a thumb screw 36 on one end thereof and has the other end thereof screw threaded as at 37 to receive screw threaded hub 38 of an adjusting arm 39. Located between the lower end of arm 39 and link 31 is a spring 40 the effect of which is to move gear 33 toward

gear 23. The spring, however, permits a variation in the distance between the two gears 23 and 33 to accommodate the size of the bundle of weft ends W between them. By turning the thumb screw 36 the arm 39 can be caused to approach or recede from the link 31 either to increase or decrease the force exerted by the spring 40. The box is closed by a cover 45 shown in Fig. 4 but removed in Figs. 5 and 6. A flat plate 46 made of sheet spring material between wall 16 and the gears acts as a brake for the latter, and openings 41 and 43 in wall 16 and plate 46, respectively, permit the aforesaid lateral movement of bearing 34. A guard G projects from wall 16 over the gears 23 and 33 to keep the threads W spaced from the inner ends of the gears.

The matter thus far described may be similar to corresponding parts found in certain prior patents to Payne, such as No. 1,842,731, and also found in my co-pending application Serial No. 518,702, filed January 18, 1944.

In carrying my present invention into effect, I provide improved means for driving the ratchet wheel 22. The driving mechanism includes an arm 50 rockably mounted on the pin 51 carried by wall 16 and carrying a resilient feed pawl 52 positioned for engagement with the teeth of the ratchet wheel 22. Arm 50 has an iron armature 55 and may be connected to a light spring 56 the effect of which is to keep the arm 50 against a fixed stop 57 on wall 16, as shown in Figs. 5 and 6.

An electromagnet 60 is secured as at 60' to the wall 16 and is placed near the armature 55 for attraction thereof. A switch 61 is secured as at 62 to the outside of the box 15, in the present instance being secured to wall 19, as shown in Fig. 5. This switch is one of the well-known so-called micro-switches and is normally open. A plunger 63 operates when depressed to close the switch. These switches are customarily furnished with two lead wires 64 and 65, respectively.

An auxiliary arm or vibrator 70 is held to arm 12 as at 71 and has a free end which vibrates during loom operation toward and away from the plunger 63. A dampener 72, shown in Fig. 4 only, may be held in the proper adjusted position along arm 70 to regulate the amount and period of vibration of the latter. I find under certain conditions that the dampener 72 is not necessary, but it is a convenient means for insuring the necessary differential vibration between arms 12 and 70.

In operation, arm 12 and vibrator 70 will vibrate differently, either as to degree or rate, or both, with the result that the free end of vibrator 70 will have a movement with respect to the plunger 63 of the switch 61. As vibrator 70 oscillates it will depress plunger 63 from time to time to close switch 61, whereupon the following circuit, indicated diagrammatically in Fig. 5, will be closed: source of electric power E, wire 80, through the electromagnet 60, wire 81, switch lead wire 65, the switch, (which is temporarily closed due to depression of plunger 63 by vibrator 70), switch lead wire 64, and wire 82 back to the source E. Closure of this circuit energizes the electromagnet and the latter attracts the armature 55, thereby moving the pawl 52 to the right as viewed in Fig. 5 to give the ratchet wheel 22 and therefore the gear 23 a partial rotation. Rotation of gear 23 is communicated through the weft threads W to the

gear 33 so that both of the thread engaging gears are caused to turn when the electromagnet 60 is energized. During loom operation the vibrator 70 will have intermittent and momentary contact with the plunger 63, and each energization of the electromagnet will be for a brief interval only, after which movement of the vibrator away from the plunger due to spring 56 will break the previously traced circuit and the arm 50 will move back to the position shown in Fig. 5. On this return movement the pawl 52 will engage the next tooth of the ratchet wheel 22 in readiness for the next closure of switch 61. This operation goes on more or less regularly so long as the loom operates.

It will be obvious that the greater the vibration of the loom the greater will be the effect of the electromagnet to turn the gears 22 and 23. The vibrator 70 is made preferably of a sheet material which is resilient and vibrates readily when the loom is in operation. When the loom stops the vibrator 70 comes to rest spaced from plunger 63 and the switch 61 will remain open. I have found in practice that the vibrator 70 tends to vibrate more rapidly than does the box 15. The electromagnet 60 is not necessarily energized for the same length of time at each depression of plunger 63. The period in which switch 61 is closed will vary, depending upon the momentary relation of vibrator 70 and plunger 63. It may in fact happen that at times the switch 61 will be closed for such a brief time that electromagnet 60 may fail to respond, but there will be other times when the switch will be closed long enough to permit adequate operation of the pawl 52. During an extended period of loom operation the switch will be closed a large number of times and for sufficient duration to give pawl 52 intermittent feeding strokes, and gears 23 and 33 will turn enough to keep the weft ends taut.

Fig. 2 shows the different relations which can exist between the weft ends and the thread gears. The weaver may place one group of threads indicated at W' near the guard G which overhangs the inner ends of the gears and place another group W2 at a greater distance from the guard in an attempt to prevent too large a group of threads from collecting at one place between the gears. The operation of the gears is such, however, that the group W2 will eventually move to the dotted line positions shown in Fig. 2. This tendency of all of the warp threads to collect in a small area accounts in part at least for the failure of previous thread holders, but does not prevent operation of my thread holder, since the electromagnet is sufficiently strong to turn the gears even though all of the threads be located close to the guard G.

From the foregoing it will be seen that I have provided simple means for actuating the thread engaging gears of a weft replenishing loom thread holder wherein an electromagnet actuates the feed pawl for the ratchet wheel connected to one of the thread gears. It will also be seen that the normally open circuit is closed intermittently due to a difference in vibration between two parts. This difference of vibration is utilized to close the switch 61 with resultant energization of the electromagnet 60. Furthermore, a degree of vibration which of itself would be insufficient to cause operation of the thread gears can, however, be utilized to control a stronger force which is adequate for proper operation of the holder.

Having thus described my invention it will be

seen that changes and modifications may be made therein by those skilled in the art without departing from the spirit and scope of the invention and I do not wish to be limited to the details herein disclosed, but what I claim is:

1. In a thread holder having geared members for the weft ends of a weft replenishing loom, electromagnetic drive means effective when energized to operate the geared members, electric circuit means effective when closed to energize said drive means, and means operative due to loom vibration to close said electric circuit means.

2. In a thread holder having geared members for the weft ends of a weft replenishing loom, electromagnetic drive means effective when energized to operate the geared members, a normally open electric switch, electric circuit means including said switch and drive means effective to actuate the latter when the switch is closed, and means operative due to loom vibration to close said switch.

3. In a thread holder having geared members for the weft ends of a weft replenishing loom, electromagnetic drive means effective when energized to operate the geared members, electric actuating means for operating the drive means, and a controller operative due to loom vibration to cause said actuating means to operate said drive means.

4. In a thread holder having geared members for the weft ends of a weft replenishing loom, an electromagnet supported by the holder, a pawl and ratchet mechanism operatively connected to the members and operated by the electromagnet when the latter is energized, an electric switch mounted on the holder, electric means effective when the switch is closed to energize the electromagnet, and means operative due to loom vibration to close said switch.

5. In a thread holder having geared members for the weft ends of a weft replenishing loom, an electromagnet supported by the holder, a pawl and ratchet mechanism operatively connected to the members and operated by the electromagnet when the latter is energized, an electric switch mounted on the holder, electric means effective when the switch is closed to energize the electromagnet, and means dependent upon loom vibration to close said switch intermittently.

6. In a thread holder having geared members for the weft ends of a weft replenishing loom, electromagnetic means effective when energized to operate the members, an electric switch electrically connected to said electromagnetic means, electric means effective when the switch is closed to energize said electromagnetic means, and means dependent upon loom vibration to close said switch intermittently.

7. In a thread holder having geared members for the weft ends of a weft replenishing loom, electromagnetic drive means effective when energized to operate the geared members, electric circuit means to energize said drive means, and means vibrating during loom operation to close said circuit means intermittently.

8. In a thread holder having geared members for the weft ends of a weft replenishing loom, electromagnetic drive means effective when energized to operate the geared members, and means vibrating during loom operation effective to cause intermittent energization of said circuit means.

9. In a thread holder having geared members for the weft ends of a weft replenishing loom, electromagnetic drive means effective when energized

10 to operate the geared members, two members which during loom operation vibrate differently, one of said members supporting said thread engaging gears, electromagnetically operated actuator means for said gears on said one member, an electric switch on one of said members opening and closing during loom operation due to vibration of said members, and electric means controlled by said switch to operate said electromagnetically operated actuator means.

11. In a thread holder having geared members for the weft ends of a weft replenishing loom, electromagnetic drive means effective when energized to operate the geared members, two members which during loom operation vibrate differently, one of said members supporting said thread engaging gears, an electromagnetic actuator on one of said members for said gears, a normally open electric switch on one of said members closed intermittently by the other member due to the difference in vibration of said members, and electric means causing energization of said actuator to effect operation of said gears when the switch is closed.

12. In a thread holder having geared members for the weft ends of a weft replenishing loom, electromagnetic drive means effective when energized to operate the geared members, two members which during loom operation vibrate differently, one of said members supporting said thread engaging gears, an electromagnetic actuator for said gears on said one member, a normally open electric switch on said one member positioned for intermittent closing by the other member due to the difference in vibration of said members, and electric means causing energization of said actuator to effect operation of said gears when said switch is closed.

13. In a thread holder unit having geared weft engaging members for the weft ends of a weft replenishing loom, electromagnetic means supported by the holder unit and effective when energized to operate said members, and electric control means controlling energization of said electromagnetic means and mounted on the unit for vibrational movement relatively to the unit.

14. In a thread holder unit having geared weft engaging members for the weft ends of a weft replenishing loom, pawl and ratchet mechanism 50 to operate said geared members, electromagnetic operating means supported by the holder and effective when energized to operate said pawl and ratchet mechanism, electric switch means supported by the unit and controlling energization of said electromagnetic operating means, and means mounted on the unit for vibrational movement relatively to the unit and effective to close said switch.

15. In a thread holder having geared members for the weft ends of a weft replenishing loom, a ratchet wheel operatively connected to said geared members, an electro-magnetic device, an armature for said electro-magnetic device extending vertically and mounted for horizontal movement 65 toward and from said device, a pawl on said armature for cooperation with said ratchet wheel, means incident to loom operation to energize said electro-magnetic device to cause the latter to attract said armature and cause said pawl to turn said ratchet wheel, and a support for said geared members, ratchet wheel, armature, and electro-magnetic device subject to horizontal vibration during loom operation.

16. In a thread holder having geared members 75 for the weft ends of a weft replenishing loom, a

support for said geared members subject to vibration during loom operation, a ratchet wheel rotatably mounted on said support and operatively connected to said geared members, an electro-magnetic device mounted on said support, a vertically extending armature pivotally mounted on said support and having a part thereof adjacent to the electro-magnetic device, a pawl on said armature for cooperation with said ratchet wheel, and means incident to loom operation to energize said electro-magnetic device, said armature tending due to vibration of the support to cause said pawl to turn the ratchet wheel independently of attraction of said armature by the electro-magnetic device, the latter when energized attracting the armature to operate the pawl and cause the latter to turn the ratchet wheel.

16. In a thread holder having geared members for the weft ends of a weft replenishing loom, a

support subject to vibration during loom operation, a ratchet wheel rotatably mounted on the support and operatively connected to said geared members, an electro-magnetic device mounted on said support, means constituting a pivot on the upper part of said support, an armature mounted on said pivot and depending therefrom and having a part thereof adjacent to said electro-magnetic device, a pawl connected to the armature and in engagement with the ratchet wheel, and means incident to loom operation to actuate the electro-magnetic device, said armature tending due to vibration of the support to cause the pawl to turn the ratchet wheel and said electro-magnetic device when energized attracting the armature and causing the pawl to turn the ratchet wheel.

HERBERT A. WHITIN.
